(57) **CLAIM**

The ornamental design for a safety helmet visor, as shown and described.

DESCRIPTION

FIG. 1 is a frontal perspective view of a safety helmet visor showing my new design secured to an exemplary safety helmet;

FIG. 2 is a perspective view thereof;

FIG. 3 is a front elevation view thereof;

FIG. 4 is a right side elevation view thereof; the left side elevation being a mirror image;

FIG. 5 is a rear elevation view thereof;

FIG. 6 is a bottom plan view thereof;

FIG. 7 is a top plan view thereof; and,

FIG. 8 is a cross section view thereof, along line 8—8 in FIG. 1.

The broken line showing of the safety helmet is for illustrative purposes only and forms no part of the claimed design.
